UNITED STATES PATENT OFFICE.

JOHN ERICKSON, OF MADISON, WISCONSIN, ASSIGNOR TO MADISON-KIPP CORPORATION, OF MADISON, WISCONSIN, A CORPORATION OF WISCONSIN.

LUBRICATOR.

Application filed January 4, 1923. Serial No. 610,618.

To all whom it may concern:

Be it known that I, JOHN ERICKSON, a citizen of the United States, residing at Madison, in the county of Dane and State 5 of Wisconsin, have invented certain new and useful Improvements in Lubricators, of which the following is a specification.

This invention pertains to improvements in force feed lubricators, the construction 10 and advantages of which will be hereinafter set forth in detail.

The lubricator in the form illustrated, is of the type shown and claimed in U. S. Letters Patent No. 1,262,979, issued to 15 William H. Putnam, under date of April 16, 1918, to which reference is had. It is to be understood, however, that the invention is not limited to the particular construction illustrated in that patent, which is 20 substantially duplicated in the present instance with the modification which forms the basis of the invention predicated thereon.

In the utilization of force feed lubricators of the type shown in the patent above referred to, and particularly where the lubricator is operated against high pressures, a pressure will be built up in the barrel as the plunger is forced down, and there 25 exists in the barrel at times, a pressure varying anywhere from approximately five to five hundred pounds or more per square inch. It has been found, in practice, that where the plunger begins to turn, as it does 30 in the construction herein described and as set forth in the patent mentioned, there is a tendency for the pressure to "spit back" through the intake port. The present invention presents a structure wherein this 35 spitting back or reflow is prevented.

In the drawings,—

Fig. 1 is a sectional elevation of so much of a lubricator as is necessary to an understanding of the invention;

45 Fig. 2 a transverse sectional view taken on the line II—II of Fig. 1;

Fig. 3 a similar view showing the pump piston as being rotated from the position shown in Fig. 2 to that where the discharge 50 port in the piston is in alinement with the discharge channel leading to the part to be lubricated;

Fig. 4 a vertical sectional elevation with the parts in the same position as shown in 55 Fig. 3; and

Fig. 5 a perspective view of the pump plunger or piston.

In the drawings, 1 denotes a casing in which are housed the various elements of the lubricator, and which casing is adapted 60 to be filled with oil and which latter is drawn outwardly in regulated quantities and forced to the point or part to be lubricated.

The operating mechanism may be said to 65 comprise a shaft 2 having a wobbling eccentric 3 mounted thereon, which functions with a yoke 4 connected by a gimbal joint to the upper end of the pump piston or plunger 5. The yoke, through the operation of the wobbling eccentric, moves the plunger up and down and likewise oscillates 70 it about its axis. The plunger carries a sector gear which meshes with a shrouded gear 75 attached to the upper part of a second piston or plunger 8 which works in the measuring chamber or cylinder 9 and which, as set forth in the patent above mentioned, serves to regulate the amount of oil which 80 may be fed into the cylinder 10 in which the pump piston 5 operates. A pipe 11 extends from the measuring pump or element 9 and feeds the oil into a pipe 12 which leads to an intake port 13 formed in the wall of the cylinder 10. A port or passage 85 14 extends from the cylinder 10 and leads to a delivery pipe, as 15, (Fig. 1), which may be extended to any point or element which is to be lubricated. The measuring 90 feature is not, however, essential to the present invention.

The construction thus far described is the same as in the patent above mentioned. The plunger or piston 5 is provided with a longitudinally extending feed port 16 and a 95 similarly positioned exhaust port 17. In the instant case the port 16 is made relatively short, that is to say, it is considerably shorter than the port 17, whereas in the patented construction above mentioned, said 100 ports are of equal height or length, or substantially so. This arrangement of the ports relieves any pressure which may be built up in the barrel or cylinder of the pumping unit, so that there will not be present a 105 pressure which will cause a spitting back through the intake port when the groove 16 comes into registry with port 13.

The operation of the mechanism may be 110 stated briefly as follows,—it being under-

stood that the yoke 4 simultaneously elevates and lowers the pistons 5 and 8 and likewise causes them to oscillate about their axes to carry the various ports into and out of registry. In Fig. 4 the pistons are moving downwardly and the intake port 16 is at such times out of registry with the intake port or passage 13. The oil which has been drawn in beneath the piston is then compressed and forced outwardly as the piston 5 moves down, the oil passing from beneath the piston out through the port or opening 14. During its downward movement, the piston is partially turned and at the limit of its downward stroke port 17 is carried out of registry with the opening 14 and port 16 is brought into alinement with the intake passage or opening 13. Owing, however, to the fact that the port 16 is relatively short, any oil or oil and air which may be entrapped beneath the piston 5 and be under pressure, will be prevented from spitting back through the port 16 and out through the intake opening or port 13, for at such time the parts are in the position shown in Figs. 1 and 2 with the upper end of the port 16 below the intake opening or port 13. This will allow the piston to move upwardly to a slight extent so as to relieve the pressure, and, in fact, may be such as to create a slight vacuum and thus assist in the drawing in of the oil as the port 16 registers with the port or opening 13. When the parts have moved up to their full extent and the measured quantity of oil is drawn from the pipe 12 into the cylinder 10 below the piston 5, the yoke will impart a movement to the pistons about their axis and bring the parts into the position shown in Figs. 3 and 4, whereupon upon a downward stroke of the piston 5 oil will be forced outwardly from beneath the same through the port 17 and exhaust port or channel 14, as above noted.

What is claimed is,—

1. In a force feed lubricator, the combination of a cylinder having intake and exhaust openings extending into the same; a piston working in said cylinder, said piston having a longitudinal port extending at one side thereof adapted to be brought into

registry with the exhaust opening in the cylinder, and a second port arranged at the opposite side of the piston, said second port being relatively short as compared to the exhaust port; and means for reciprocating said piston and oscillating the same about its axis, whereby the ports will be alternately brought into alinement or registry with the respective openings in the cylinder and the intake port caused to function with the intake opening only after the piston has moved outwardly to a greater or less degree upon its intake stroke. 55

2. In a force feed lubricator, the combination of a cylinder having intake and exhaust openings extending into the same; a piston working in said cylinder, said piston having a port upon one side thereof adapted to be brought into registry with the exhaust 60 opening in the cylinder, and a second port arranged at the opposite side of the piston adapted to be brought into registry with the intake opening; means for reciprocating said piston and oscillating the same about 65 its axis, the ports being so arranged as to be simultaneously out of registry with the openings when the piston begins its intake stroke, whereby the ports will be alternately brought into alinement or registry with the 70 respective openings in the cylinder and the intake port caused to function with the intake opening only after the piston has moved outwardly to a greater or less degree upon its intake stroke. 75

3. In a force feed lubricator, the combination of a cylinder having an intake and an exhaust opening; a piston mounted in the cylinder; means serving to reciprocate the piston and likewise to oscillate the same about its axis; and an exhaust and an intake port formed in the piston, cooperating with the openings aforesaid, the intake port being so arranged with reference to the intake opening as that the intake port and its opening will not register during the initial suction movement of the piston, and immediately after the exhaust port is closed. 80

In testimony whereof I have signed my name to this specification.

JOHN ERICKSON.
